(57) **CLAIM**

The ornamental design for a surface configuration of an instrument display for a vehicle, as shown and described.

DESCRIPTION

FIG. 1 is a front view of a surface configuration of an instrument display for a vehicle according to our novel design;

FIG. 2 is a right perspective view of the surface configuration of an instrument display for a vehicle according to our novel design; and,

FIG. 3 is a left perspective view of the surface configuration of an instrument display for a vehicle according to our novel design.

The dash lines included in the drawings depict environment and are not part of the claimed design.
